ENGINE FUEL TEST DEVICE

Blanchard L. Mickel, Munster, Ind., assignor to Standard Oil Company, Chicago, Ill., a corporation of Indiana
Filed Apr. 29, 1960, Ser. No. 25,577
2 Claims. (Cl. 73—61)

This invention relates to a laboratory apparatus for testing fuel compositions for use in internal combustion engines. This invention further relates to an improved engine fuel test device for giving indications of deposit forming and removing properties of fuel compositions which indications may be correlated with deposit forming and removing properties of the sample as a fuel in an operating internal combustion engine, particularly with regard to deposit weight and deposit movement in the fuel-induction system of an internal combustion engine.

In the development of new fuel compositions by blending as well as by formulating with addition agents, gum and varnish deposition and particularly deposits on the fuel-induction system of an internal combustion engine under conditions of operation of the engine are a major concern. It is desirable to formulate engine fuel compositions so that they will function without leaving such deposits and sometimes with the additional ability to remove deposits which have already been formed within the engine.

In an internal combustion engine, deposits may form from the fuel under action of heat in the fuel-induction system. The deposits may then either accumulate within the induction system and cause intake valve-sticking, etc. or they may move through the induction system and into the combustion chamber without accumulating. Once in the combustion chamber, the deposits may be eliminated through normal combustion processes within the combustion chamber. Deposit movement, as discussed herein, relates to the movement of deposits through the fuel-induction system.

The fuel-induction system is the system through which fuel passes in an internal combustion engine before entering the combustion chamber. For example, in a spark-ignition internal combustion engine, the fuel-induction system generally is defined as that series of passageways between the carburetor throttle plate and the underside or "tulip" portion of the intake valves. The mixing of fuel and air is generally just upstream of the throttle plate and the fuel-air mixture passes around the throttle plate before entering the network of passageways which lead to the individual combustion chamber. En route to the combustion chamber, the fuel-air mixture encounters conditions which may lead to the formation or separation of harmful fuel deposits. At the throttle plate, in the nearly closed idling position, deposits which seriously restrict air-fuel flow may be formed or thrown out of suspension or solution. Such deposits may lead to rough idling and engine stall.

A second point where deposits may form is on surfaces adjacent to the carburetor-heat porting. Here, hot exhaust gases are diverted from the exhaust manifold into the area around the carburetor base for the purpose of improving fuel vaporization and reducing carburetor icing; surface temperatures of several hundred degrees may be encountered. Fuel droplets which contact this hot surface are immediately vaporized but the non-volatile fuel components and impurities may remain behind on the hot surface to be oxidized or thermally cracked, thereby forming gumlike deposits or gum-precursor materials.

While thin varnish films in the vicinity of the carburetor-heat porting may not be directly harmful, real difficulties

2

may occur in yet a third area, that of the intake valves and ports.

The induction-system surfaces upstream of the intake valve may be considered to be a reactor in which heavy ends are generated by flash distillation and gum and gum precursors are formed or separated from the fuel. This mixture of heavy ends and gum-like materials is thought to migrate, as a thin liquid film, downstream and into the vicinity of the intake valves. Temperatures as high as 600° F. may prevail on the intake valve surfaces. When the moving film of heavy ends flows onto the hot valve surfaces, further oxidation as well as cracking and coking may occur. The formation of deposits on valves and port surfaces is thought to be further aggravated by the flashback of hot combustion gases as well as by certain lube-oil additives and components. If the fuel has little deposit-forming tendency, then it is unlikely that engine damage will occur. If the deposits formed are not adherent, but instead, are swept downstream and into the combustion chamber, then again, valve damage is unlikely. However, if the fuel tends to form deposits which are both large in quantity and adherent in nature, then the sticking (and subsequent burning) of valves and reduction in volumetric efficiency and performance is very probable.

Any proposed new fuel composition produced in the laboratory must be extensively tested before it may be used as a commercial engine fuel. Laboratory tests, although they are helpful and enable the researcher to foresee certain deposit forming tendencies of engine fuel, are generally not entirely reliable; many of the test procedures do not give results which are correlated with results under engine operation. After passing the laboratory tests, proposed fuel compositions are then subjected to expensive and time-consuming engine tests which are actually conducted in an internal combustion engine under operating conditions. Some such engine tests take up to a week or more to run and because of the limited number of engines available for engine tests, it is desirable to screen out as many proposed fuel compositions as possible by a laboratory technique or with a laboratory device. Laboratory devices do not give adequate definitions or measurements of deposit movement within an engine.

The present invention provides a fuel testing device for testing engine fuels, which device gives results with regard to gum or deposit forming and removing properties of a fuel and particularly with regard to deposit weight and deposit movement through the induction system of an internal combustion engine. The results obtained using the present device are correlated with results obtained in the induction system of an operating internal combustion engine. The device of this invention may be used in a technique for determining deposit movement and weight in a minimum of time and with little fuel expenditure. The device is particularly useful in screening samples of fuel compositions in a laboratory, thereby eliminating many of the actual engine tests necessary during development of a fuel.

The device of this invention provides a rotatable heated conduit which is removable from the heating source and is interchangeable with other conduits. Means for rotating the conduit in heatable proximity to the heating source are also provided. The conduit is positioned at an inclined angle to provide gravity flow therethrough from an upper end to a lower end. The heating source may be capable of providing preselected temperatures within the range of from about 100 to about 700° F. or higher. The conduit is provided with fuel and air inlet means at the upper end and outlet means at the lower end. As a technique for determining deposit forming or removing properties of a fuel composition, the

conduit is heated to a preselected temperature and fuel and air are introduced at the inlet and flowed by gravity through the conduit while rotating the conduit. The deposits formed in or removed from the conduit are then measured and the measurement is taken as an indication of the fuel composition properties. The conduit may then be prepared for another test run such as by cleaning or may be replaced by another conduit. It is important that the conduit be capable of being continuously rotated; rotation of the conduit during use of this device provides a large evaporating surface, symmetrical with regard to gravity, and thereby permits use of a shorter conduit than would be possible without such rotation.

FIGURE I illustrates an embodiment of the device of this invention.

FIGURES II to IV illustrate alternative forms of heating means usable with the device of this invention.

With reference to FIGURE I of the drawings and with reference to the embodiment illustrated therein, conduit 11 is provided in chamber 12 within best receiving proximity to heating means 13. Conduit 11 is elongated and of such configuration so as to provide substantial lateral and bottom confinement of a fluid engine fuel flowing from end to end therethrough. Conduit 11 is preferably essentially straight to allow proper rotation and free flow of an engine fuel fluid therethrough without permitting appreciable amounts of the fluid to collect at any point along the conduit. The conduit is readily removable from chamber 12 and heating means 13 and is interchangeable with other conduits. For any series of tests of a fuel or fuels to be used for comparison purposes, the same basic configuration of conduit 11 must be used. Conduit 11 is constructed of a solid material which is heatable within the range of from about 100° F. to about 700° F., such as, for example, glass, carbon steel, stainless steel, other alloy steels, galvanized steel, brass, copper, silver, aluminum, Bakelite, and the like. Where conduit 11 is a tube, glass is a preferred material since it allows visual observation of the deposits as to their position and nature within the tube. Conduits of different materials may be provided and may be interchangeable for alternating use, e.g., for the purpose of determining the effects of such different materials on gum deposition. Conduit 11 is rotatably fitted within the chamber of heating means 13 with sufficiently snug fitting to retard its longitudinal gravitational movement from chamber 12 but sufficiently loose to permit rotation of conduit 11 within chamber 12. Conduit 11 is thereby held in heatable association with heating means 13 and is rotatable during use.

Chamber 12 within heating means 13 is an elongated chamber through heating means 13 and is adapted to receive conduit 11 as hereinabove described. Chamber 12 may be an elongated tube, such as for example a metal tube, in which conduit 11 is snug fitted or chamber 12 may simply be a passageway or space provided within heating means 13 such as illustrated in FIGURE I, or may be constructed as a part of heating means 13. Chamber 12 is in any event advantageously provided with means for assuring the snug rotatable fit of conduit 11 therein such as is provided by the snug packing of insulation 16 around conduit 11 at each end of chamber 12 as illustrated in FIGURE I or as may be provided by finger projections, ribs or rings within chamber 12 at various positions along chamber 12, such as for example, at each end of chamber 12.

The heating means may be any means capable of heating conduit 11 and maintaining a preselected constant or gradient temperature in conduit 11. The heating means may advantageously be an electrically operated heating coil controlled at a pre-selected temperature by thermostats in the wall of conduit 11. In the embodiment of FIGURE I, the heating means includes a heat exchange jacket 13 surrounding conduit 11 and adapted

for flow of heat exchange fluid therethrough. The heat exchange fluid is supplied by boiler 27 and condenser 29. A liquid of constant boiling point is charged to boiler 27 and heat is applied by heat source 28 which may be a gas burner, electrical heating coil, furnace, etc. The liquid in boiler 27 is vaporized and charged as a heat exchange fluid to jacket 13 through line 27a. The vaporized fluid condenses in jacket 13 and/or reflux condenser 29 attached to jacket 13 by means of line 29a and is returned to boiler 27 for revaporation. Conduit 11 is heated by heat exchange with jacket 13.

Examples of constant boiling liquids and temperatures which may be obtained in conduit 11 with each are as follows: 1-2-dichlorobenzene (about 350° F.), methyl benzoate (about 390° F.), m-xylene (about 280 to 285° F.), 1,2,4-trichlorobenzene (about 415 to 420° F.), and benzoic acid anhydride (about 675° F.).

Jacket 13 is conveniently provided with insulation 16 to conserve heat and protect personnel from burns.

Conduit 11 is mounted on a slope by mounting means, (not shown) to provide gravity flow therethrough. The illustrated slope is about 15° although it is to be understood that any slope can be used as will provide adequate flow. The mounting means may be any such means known to the art such as, for example, an assembly of clamps and bar stands as are used to position condensers and the like, a sling arrangement, an inclined surface, a supporting block, etc. The mounting means may advantageously be adjustable to provide a number of differing degrees of slope or inclination in order to regulate gravity flow rate through and fluid residence time within conduit 11. Conduit 11 is thus positioned on an inclination providing an upper inlet end 9 and a lower outlet end 10. Inlet end 9 of conduit 11 is provided with fuel inlet line 18 and air inlet line 19. Fuel inlet line 18 is advantageously provided with fuel meter means such as syringe 22 and air inlet line 19 may advantageously be provided with air meter means such as air meter 21.

Lines 18 and 19 communicate with the interior of conduit 11 through chamber 14 in coupling 15 and through upper end 9. Conduit 11 is journaled to coupling 15 in such a manner as to permit rotation of conduit 11 without resulting rotation of coupling 15 and lines 18 and 19.

Syringe 22 is a plunger-type syringe adapted for measuring fuel samples and constitutes the fuel meter means in the embodiment of FIGURE I. Plunger 23 is provided with worm gear receiver 24 which may be a tube having projections complementing worm gear 25 for translation of rotational movement of worm gear 25 into linear movement of receiver 24 and plunger 23. Worm gear 25 and receiver 24 comprise a worm gear linkworks assembly. Drive means 26, for example a constant speed electric motor, drives worm gear 25 at constant speed resulting in linear movement of plunger 23 within syringe 22 in a direction to provide flow of fluid from syringe 22 through line 18 at a constant rate.

At outlet end 10 of conduit 11, is outlet coupling 37 containing outlet chamber 35. Passing through chamber 35 is a rotatable extension conduit 32 which is rotatable with relation to coupling 37. Extension conduit 32 has a flared end 31 into which conduit 11 is friction fitted at lower end 10. On extension conduit 32 and within chamber 35 is an opening 34 adapted to permit flow of fluid from extension conduit 32 into chamber 35. Vent 36 is provided communicating within chamber 35 for withdrawing fluids from chamber 35. Vent 36 may conveniently be fitted with a vacuum pump (not shown) or the like to provide better flow of fluids from chamber 35.

Drive means, such as constant speed electric motor 33, are provided to rotate extension conduit 32 which in turn rotates conduit 11 through the fitted connection of flange 31 at lower end 10. Thus, the drive means is adapted to rotate an elongated conduit assembly formed by conduit 11 and extension conduit 32. Couplings 15

and 37 are affixed in stationary position with relation to the rotatable conduit assembly.

Drive means 33 and drive means 26 may be controlled such as, for example, by control means 38, which may be a timer switch, for concurrently activating and deactivating both drive means, such as by control through leads 39a and 39b and leads 40a and 40b respectively.

As shown in FIGURES II and III respectively, in lieu of boiler 27, jacket 13 and condenser 29 of the embodiment of FIGURE I, an electrically operated heating coil 50 or a plurality of electrical heating coils may be used in heating conduit 11 in the apparatus of FIGURE I. Also, in lieu of boiler 27, jacket 13, condenser 29 and insulation 16, there may be employed a tapered electrical resistance element 70 as shown in FIGURE IV. The tapered resistance element maintains a temperature gradient along conduit 11 by resistance heating; such a temperature gradient may also be maintained by using coils of different resistance as coils 60, 61 and 62 of FIGURE III or by varying the coil spacing of coil 50 in FIGURE II. Such means for obtaining a temperature gradient are known to the art.

Supports or holding means (not shown) may be provided to support or position various elements of the device wherever desired or needed. For example, such supports may be provided to hold couplings 15 and 34 and heat exchanger 13 and insulation 16 stationary while rotating the conduit. Supports may also be provided for drive means 26 and 33, timer switch 38, air meter 21, reflux condenser 29, boiler 27, heat source 28, and other elements as desired or needed.

In operation, with reference to FIGURE I, a sample of fuel to be tested is introduced into syringe 22 and conduit 11 is brought to the desired temperature by heating boiler 27 containing a heat exchange fluid. Timer switch 38 is then turned on and drive means 33 and drive means 26 are thereby activated. The fuel sample flows through line 18 and a partial vacuum applied at vent 36 draws air through air meter 21 and line 19. The air meter may be used to control the rate of flow of air if desired. Only sufficient amounts of air are necessary to keep the interior service of conduit 11 swept free of vaporized fuel. This amount of air is below that amount necessary to produce a flammable or explosive fuel-air mixture.

Fuel from line 18 and air from line 19 are charged through chamber 14 in coupling 15 and into conduit 11 which is being rotated at a constant speed by drive means 33. The fuel and air are heated in rotating conduit 11 and continue flowing through conduit 11 into conduit extension 32, and chamber 34 and are withdrawn from the device through vent 36. After the total sample in syringe 22 has been charged through conduit 11, drive means 26 and 33 are deactivated by timer switch 38. Timer switch may be provided with automatic means for deactivating drive means 26 and 33 after a pre-estimated length of time for the test.

After the test sample has been completely run, conduit 11 is removed from chamber 12 by disengaging conduit 11 from the friction fit with flange 31 and from the journal fit with coupling 15. Conduit 11 is then pulled out endwise from chamber 12.

The deposits in conduit 11, after each test, are measured for deposit weight and for deposit movement. The deposit weight may conveniently be determined by subtracting the weight of conduit 11 before the test from the weight after the test. With regard to deposit movement, the gum and deposits appear as elongated streamers on the inner surface of conduit 11. The number of such streams appearing is determined and a measurement of each streamer is taken. The measurement of each streamer is the distance from upper end 9 of conduit 11 to (1) the trailing edge of, and (2) the furthest point of travel of each measured streamer within conduit 11. It is probable in many tests that no trace of streamers

will appear in the upper end of conduit 11, however, the measurement from the upper end to the furthest point of travel of the streamer is still taken as a measurement of deposit movement.

- 5 During the operation of the device of this invention, with reference to the actual formation of gum and deposits in streamers within the rotating conduit, fuel and air are charged through the heated rotating tube and deposits form in and/or separate from the fuel-air mixture.
- 10 The fuel-air mixture is maintained in contact with the rotating surface within the conduit and sufficient air is swept through the conduit to carry fuel vapors out of the apparatus, e.g. into a vacuum system. As the fuel proceeds down the conduit, light ends are distilled off leaving the
- 15 heavy ends and gum precursors which are then free to react and further distill until, at some point intermediate the upper and lower ends of the conduit, viscosity of the liquid film formed on the inner surface of the conduit increases to the point that further movement down the
- 20 conduit is halted. Thus, at the end of a test, the distance which the deposits have moved is measured and the deposits are weighed, e.g. after removal from the conduit. Distances of deposit movement correspond to distances of the leading edge and/or trailing edge from the conduit inlet. It is important that the conduit be rotated since, by so rotating, a large evaporating surface, symmetrical with regard to gravity, is provided. The large evaporating surface also permits overall shortening of the apparatus and savings therefrom.
- 25 Although, in the above descriptions, the heating means provided a constant temperature within the conduit throughout the test, the heating means may also be one capable of providing a temperature gradient along the length of the conduit from one end of the conduit to the
- 30 other end of the conduit, such as may be attained by using a plurality of electrical heating coils or a tapered electrical resistance element. Where a gradient temperature is provided over the length of the conduit, it may be advantageous that the lower temperatures be at the inlet of the conduit and the higher temperatures be at the outlet of the conduit. Further, such temperature gradient, when used, may be such as to provide temperatures differing by at least about 50° F. along the length of the conduit. Such gradient temperatures may be used to determine
- 35 properties of fuels under changing temperature conditions such as are found in an internal combustion engine. Based on my study of fuels with this device, I believe that a temperature gradient along the conduit does not substantially increase accuracy or correlation of the device with
- 40 actual engine tests, and therefore, I prefer the use of a constant temperature along the conduit in view of its greater ease of attainment.
- 45 The conduit used for one test may be cleaned with appropriate solvents and may be reused in subsequent tests if desired.
- 50 The device provided herein has become known as the "Rotogum" tester and will, at times, be hereinafter referred to as such, or by like name. The test conducted in the Rotogum tester will be referred to as the Rotogum test.
- 55 Correlation between the Rotogum tester and several laboratory engine tests was studied. The performance with each of 18 fuel-additive blends in the Rotogum test was compared with performance in the Lauson Engine Induction System Deposit test (Lauson Engine test) and
- 60 the Union Induction System test (Union test.) The test procedures were as follows:

Lauson Engine Test

- 65 70 The Lauson Engine tests were run in accordance with a procedure described in a paper entitled: "Evaluating Gasolines for Induction System Gums" by C. C. Moore, J. L. Keller, W. C. Kent and F. S. Liggett, presented before the SAE National Fuels and Lubricants Meeting in Tulsa, Oklahoma, held November 4-5, 1954 (available as Pre-
- 75

print No. 406 from the SAE Special Publications Department).

Union Test

The Union Induction System tests were run in accordance with the description in ASTM Special Technical Publication No. 202, Symposium on Vapor Phase Oxidation of Gasoline, ASTM, Philadelphia, Pennsylvania, June 1957, pp. 21-40, formerly presented at the Second Pacific Area National Meeting of the above symposium at Los Angeles, California, September 19, 1956.

Rotogum Test

The apparatus used in this test procedure was a resistance furnace consisting of an insulated heating element positioned around a 40 cm. length of glass tubing having about a 1 1/4 cm. internal diameter. The glass tube constituted the conduit through which each sample tested was flowed. The conduit was on an inclined slant at an angle of about 30°. The glass tube was removable and replaceable with other like glass tubes. A Variac was used to maintain a temperature of about 400° F. within the tube and the temperature was controlled responsible to thermocouples within the tube. Each sample tested had a volume of 100 ml. in the liquid state at room temperature and each sample was allowed to flow through the glass tube at a sample injection rate of about 2.5 ml. per minute. The glass tube was rotated at a constant speed of about 72 r.p.m. The air flow rate into the glass tube was controlled to provide a very rich fuel-to-air mixture by providing less than stoichiometric amounts of air in the glass tube relative to fuel. The flow of air was, however, fully sufficient to carry vapors from the tube. The tube was removed after each sample and the total weight of deposits was determined. The length of movement of streamers from the inlet and the numbers of streamers were also determined.

The above three test procedures were run on leaded gasoline compositions (3 cc. of commercial tetraethyllead fluid) containing various addition agents. Eighteen different fuels were used in preliminary tests to determine the correlation of the Rotogum test with an engine test, i.e. the Lauson Engine test.

Correlation between the Rotogum and the Lauson Engine tests was studied with regard to the performance of the above-mentioned 18 fuel-additive blends tested by each procedure. The degree of correlation between the test units was expressed in terms of the Spearman Rank Correlation Coefficient. This coefficient is expressed as rho in the following formula:

$$\rho = 1 - \frac{\sum d_2}{(n^3 - n)}$$

wherein d is the numerical difference in rank (the quality sequence) between Lauson and Rotogum test results of the same fuel and n is the total number of fuels which were compared in the two units. Had the performance or quality sequence of the 18 fuels, as determined in the Rotogum test, been identical to that from the Lauson test, there would be perfect correlation and rho would be equal to unity. If there were no correlation at all, then rho would equal zero.

Correlation of deposit weight was also studied by comparing weight of the deposits resulting in each test.

Rotogum results in correlation with Lauson engine results may also be represented in terms of deposit movement. The deposit movement (DM) term is expressed as follows:

$$DM = \frac{[200 - \sum (X_t - X_1)]}{200}$$

wherein X_t is the distance in cm. which the trailing edge of each deposit streamer lies from the fuel inlet and X_1 is the distance of each streamer leading edge from the inlet.

Rotogum results may also be expressed in terms of an integrated expression, the Rotogum rating (RR), as follows:

$$5 \quad RR = 0.5 \left(\frac{\text{mg. deposit}}{5} + \left[\frac{200 - \sum (X_t - X_1)}{200} \right] \right)$$

Correlations between the various Rotogum criteria and Lauson performances of the 18 fuels were as follows:

10	Rotogum criteria:	
	Deposit weight	0.81
	Deposit movement	0.79
	Rating	0.85

The above reported rho values show that there is a significant correlation between the Rotogum and Lauson tests. Further, the interaction of deposit weight and deposit movement terms, as expressed by the Rotogum rating, is more closely related to engine performance than either deposit weight or deposit movement terms individually. By way of comparison of correlation with the Lauson test, the Union Induction System Apparatus used in the Union test, gave a rho value of 0.72 in tests of the same 18 fuels.

Limited full-scale multi-cylinder engine laboratory tests also have shown good agreement with the Rotogum tester. Additives which improve performance in the Rotogum test also reduced induction system deposits in Chevrolet 6 and Oldsmobile V-8 engines. It has also been observed that certain additives which increase deposit movement in the Rotogum apparatus also function as carburetor detergents in tests conducted with a Pontiac V-8 engine.

Precision of the Rotogum device, in terms of weight deposit, has also been found to be good. Standard deviations, expressed as percents of the mean of from 8 to 10 tests using the same fuel, were as follows:

Test:	Standard deviation, percent
Lauson engine	±38
Union induction system	±20
Rotogum	±15

The Rotogum device gives precise data in the same or a lesser amount of time than either of the other two tests considered above, even though the Rotogum tests are run in duplicate for improved calculated precision.

It is evident from the above that I have provided a new device and testing procedure for determining deposit properties of engine fuel compositions and particularly such properties as relate to deposit weight and deposit movement in the fuel induction system of an internal combustion engine. The results obtained are correlated with results obtained in an actual operating internal combustion engine.

I claim:

1. An engine fuel test device for indicating gum and deposit forming properties of an engine fuel which device comprises a jacket heating means having an elongated chamber, a heatable and rotatable elongated conduit within said chamber and longitudinally and rotatably moveable within and removable from said chamber, stationary inlet means at a first end of said conduit for charging fluid engine fuel and oxygen-containing gas to said conduit, said stationary inlet means having inlet coupling means attached to said rotatable conduit, means for metering the flow of engine fuel and oxygen-containing gas to said conduit, said means including a plunger driven means for metering said engine fuel, stationary outlet means at a second end of said conduit, said stationary outlet means having outlet coupling means attached to said rotatable conduit, said conduit being adapted for rotation on an axis extending between said inlet means and said outlet means and substantially connecting said inlet means and said outlet means, means positioning said conduit on a slope whereby longitudinal gravity flow is provided from said inlet means to said outlet means, an inner surface within said conduit and capable of collecting gums

and deposits, temperature control means for controlling the temperature of said inner surface at a preselected temperature within the range of from about 100° F. to about 700° F., motor driven means for rotating said conduit on said axis at a substantially constant speed, time actuated means for controlling said motor driven means for rotating whereby said means for rotating is capable of activation and deactivation, and means permitting the removal of said conduit from said chamber whereby gum and deposits on said inner surface may be measured as an indication of gum and deposit properties correlated with the gum and deposit weight and movement tendencies of said engine fuel in the fuel-induction system of an operating internal combustion engine.

2. An engine fuel test device for ascertaining the mobility and weight of gum and deposits through the fuel-induction system of an internal combustion engine where gum and deposits are formed in the fuel, which device comprises a heating jacket adapted for flow of heating fluid therethrough, a rotatable heatable elongated cylindrical conduit removably positioned within said jacket in heat receiving proximity to said jacket, means positioning said jacket containing said conduit on an inclined slant whereby the two ends of said conduit are definable as an upper end and a lower end with relation to each other, said inclined slant being sufficient to provide gravity flow of fluid fuel through said conduit from said upper end to said lower end, at said upper end an inlet coupling containing an inlet chamber communicating within said upper end of said conduit, said upper end being journaled 30

in said inlet coupling, an air conduit communicating with said inlet chamber for carrying air to said inlet chamber, a plunger-type syringe adapted to charge fuel to said inlet chamber, a constant speed first electric motor, worm gear link-works positioned between said first motor and the plunger of said syringe and adapted to convert the rotary movement of said motor into linear movement of said plunger within said syringe, at the lower end of said conduit, a removably connected rotatable cylindrical tubular extension of said conduit, said extension being friction connected to said lower end and rotatably protruding through an outlet coupling having an outlet chamber, means for fluid communication between said outlet chamber and the interior of said extension, means for withdrawing fluid from said outlet chamber, a constant speed second electric motor adapted to rotate said extension and said conduit, and timer switch means for controlling said first and second motors and providing concurrent activation and deactivation of said motors.
